UNITED STATES PATENT OFFICE

2,543,238

MECHANICAL MOVEMENT

Joseph Emile Everard, Cochrane, Ontario, Canada

Application March 16, 1945, Serial No. 583,093

1 Claim. (Cl. 74—54)

1

This invention relates to liquid feeding apparatus that is particularly adapted to the feeding of liquid reagent to milling circuits in ore processing.

The invention is illustrated by its reference to ore processing. Milk of lime is used widely in milling circuits as a protective agent for the cyanide. It must be maintained in given percentage in the cyanide solution since if the lime content drops too low or the alkalinity disappears entirely the cyanide is destroyed by the action of the ores. This is a condition which has had to have careful supervision and the introduction of such a reagent usually has been accomplished previously by using a mixing box adding water and lime thereto, agitating the mixture from time to time, causing it to pass through a screen and draining a quantity therefrom from time to time during the working day to introduce at least a sufficient quantity of the mixture to the processing solution to avoid deterioration of the cyanide. This procedure is usually performed manually and at intervals sometimes of considerable and not always uniform duration and results in the percentage of reagent in the circuit varying greatly at different times.

This procedure has obvious disadvantages, both in respect to variation in percentage of reagent in the circuit during the day and the necessity of following this procedure at intervals throughout the twenty-four hour period.

The present invention avoids these disadvantages and provides a means for minute control of the feeding of reagent in milling circuits or for the feeding of liquid in other fields in a similar manner.

It is an object of the present invention to provide liquid feeding apparatus automatically operated which automatically will feed a predetermined amount of liquid at regular intervals of such short and uniform duration as to give the effect of a continuous feed.

A further object of the invention is to provide an apparatus of this kind by which liquid may be automatically fed through a plurality of independent conduits in a regular and controlled manner.

A further object of the invention is to provide an apparatus of this kind which may be adapted to feed liquid from a tank to a plurality of separate conduits wherein the amount discharged into each conduit may be selectively varied and the time of introduction of the liquid may be varied as between any of said conduits.

A still further object of the invention is to provide a liquid feeding apparatus of this kind which

2

is particularly simple in construction and which may be installed and maintained with a minimum of difficulty.

A still further object of the invention is to provide apparatus of this kind including indicating means operating in conjunction with the feeding means for indicating the amount of liquid which is periodically fed from the tank.

With these and other objects in view, the invention is for use with a tank having liquid feed outlet or outlets. The invention relates to a device for periodically operating a valve for one of the outlets from a normal position comprising, a frame, a valve actuating arm pivotally mounted on said frame, said arm having a telescoping section control means for telescoping said telescoping section, a cam, and drive means for the cam. The free end of the telescoping section is formed for engagement with the cam. A dial and pointer for the dial, and a link and gear system connecting the pointer and the telescoping section of the arm are also provided.

The invention will be clearly understood after reference to the following detailed specification read in conjunction with the drawings.

In the drawings:

Fig. 1 is a partly sectional view of a feeding tank showing the liquid feeding apparatus mounted in conjunction therewith, said apparatus being shown mainly in side elevation.

Fig. 1a is a fragmentary detail of part of the regulating arm shown in Fig. 1 and illustrating the journal connected thereto for moving the arm on the cross shaft.

Fig. 2 is a top plan view of a tank having a battery of feeding devices according to the present invention mounted in conjunction therewith including a common means of operation for each of them.

Fig. 3 is a side elevation of Fig. 2.

Fig. 4 is an end elevation of Fig. 2.

Fig. 5 is an enlarged top plan view of the regulating arm and actuating parts of the liquid feeding apparatus.

Fig. 6 is a fragmentary detail showing the lever and quadrant for operating the indicating means.

Fig. 7 is a partly sectional detail taken substantially along the line 7—7 of Fig. 1.

Fig. 8 is a detail elevation of part of the supporting structure for the indicating means and,

Fig. 9 is a sectional detail of an alternative form of valve structure.

Referring to the drawings, 10 indicates a tank containing a liquid designed to be fed in a controlled manner such as a reagent to be fed in

ore milling circuits. This tank is provided with a valve outlet 11 which in the present illustration is controlled by a valve 12 actuated by an actuating rod 13. The valve structure includes a body 14, which may be of tubular form, surrounding the seat of the valve outlet 11 and housing a suitable coil spring 15 which is pressed against the valve 12 by means of a suitable screw threaded cap 16 mounted on the body 15. The body 14 is orificed or formed with open portions to permit the liquid in tank to discharge through the valve outlet 11 when the valve 12 is lifted from its valve seat.

Mounted on the tank 10 by any suitable means, such as the transverse support in structure 17, is a valve actuating arm 18 which is pivoted on the transverse shaft 19 intermediate its ends. Pivoting is effected by means of a suitable bracket 20 carried on the arm and designed to swing about the shaft 19 which is carried by suitable brackets 21 mounted on the supporting structure 17.

The arm 18 is longitudinally recessed to form the guideway 22 which, as shown in Fig. 7, is undercut to retain and permit sliding operation of the slide 23. An upwardly projecting plate or bracket 24 is rigidly fastened to the slide 23, plate 24 being provided with a screw threaded orifice through which the screw threaded portion 25 of the adjusting member 26 projects. The adjusting member 26 is rotatably carried in the projecting bracket 27 which is rigidly mounted on the arm 18. Thus by turning the wheel 28 of the member 26, the latter freely rotates in the bracket 27 and the consequent rotation of the screw threaded portion 25 will cause the plate 24 to move longitudinally of the arm, in a forward or rearward direction as the case may be.

The slide 23 projects beyond the end of the arm 18 and is rigidly fastened to a fitting 29 which carries the roller 30. This latter is disposed in the path of a rotatable cam 31 carried on the shaft 32. Thus it will be apparent that contact of the cam with the roller 30 in the downward swing of the cam will tilt the arm 18 about its pivotal shaft 19. Moreover by adjusting the adjusting member 26 so as to project the fitting 29 beyond the end of the arm 18 to a greater degree, the roller 30 will be positioned closer to the cam 31. Consequently in its downward swing the cam 31 will engage the roller for a greater degree of time. Therefore the arm 18 will be caused to swing downwardly to a greater degree and its operation will extend over a greater period of time.

The downward depression of the arm 18 will, when it swings about its pivotal shaft 19, lift the opposite end of the arm and, by reason of the connecting rod 13, which is connected to this opposite end of arm 18 by means of the universal joint connection 33 and ball and socket connection 34, will cause a lifting of the valve 12 thus to open the valve outlet 11. Furthermore, having regard to the adjustment of the fitting 29 towards or away from the cam 31, by the flow adjusting wheel 28, the valve 12 may be removed from its seat over a greater or lesser period of time thus to vary the amount of liquid discharged from the tank 10 through the valve opening 11. The valve 12 is then returned to its seat by the spring 15 when the cam 31 disengages from the roller 30.

The amount of liquid periodically discharged from the tank 10 may be set on a suitable scale 35 which is provided with the pointer needle 36 carried on the shaft 37. This latter shaft is, as

particularly shown in Fig. 7, freely journalled in the frame members 38 and 39 and carries the spur gear 40. This is designed to mesh with the quadrant 41 (Fig. 6) which, by means of the arm 42, is adjustably mounted on the lever 43, the latter being pivotally mounted as at 44 from its lower end on the general supporting bracket 45 (Fig. 7) carried by the supporting structure. An actuating rod 46 is fastened as shown in Fig. 7 to the plate 24 and extends upwardly substantially parallel to the lever 43. This is link-connected by the link connection 47 with lever 43 as shown in Fig. 1 the link being adjustably connected with lever 43 and the actuating rod 46 by means of the series of holes 48 provided in each. Thus, when the adjusting member 26 is rotated to move the fitting 29 towards or away from the cam 31, the consequent movement of the plate 24 in operating the slide 23 will likewise move the actuating rod 46. The movement of this latter rod is imparted by the link 47 to the lever 43 which is thus caused to swing about its pivot 44. The swinging quadrant 41, which rotates the spur gear 40, will cause the needle shaft 37 to rotate, likewise rotating the needle 36 to indicate on the scale or dial 35 the adjustment which has been effected to increase or decrease the quantity of liquid discharged. Therefore by simply adjusting member 26 by flow wheel 28, according to the desired volume of liquid it is desired to discharge from the tank 10 periodically, this selected uniform amount may be discharged for the purposes required.

The cam shaft 32 is operated by the pulley 49 belt connected to the pulley 50 which is operated from the reduction unit 51. The latter in turn is operated through the shaft 52 which is provided with a drive pulley 53 connected to the motor drive pulley 54 carried by the motor 55. Moreover the shaft 52 carries the worm 56 designed to mesh with the worm wheel 57 on the vertical shaft 58, the latter carrying a suitable agitator 59 which extends within the tank 10. Consequently as the liquid is discharged from the tank 10 periodically in the automatic manner described it is also automatically stirred to maintain constituents of the mixture in proper suspension where this is necessary. For this reason and due to the construction and method of operation of the valve, the apparatus is particularly well suited to the feeding of liquids containing solid and even granular material in suspension.

The valve outlet 11 may discharge to any suitable discharge nozzle or pipe line such for instance as the nozzle 60 (Fig. 3) which discharges into the pipe 61 to be delivered at the appropriate point. Moreover as will be clearly noted from a consideration of Figs. 2 and 4, the development is readily adaptable to the control of a series of valves, which will discharge through the appropriate nozzles (Fig. 4) into a corresponding number of pipe lines to be delivered to the appropriate destinations required. In this instance it will be apparent that a valve and control unit as described in detail above is associated with each outlet and, as shown particularly in Fig. 2, these units are operated from the single cam shaft 32 employing the appropriate number of cams designed to engage the corresponding roller of each fitting 29. Finally it will be apparent that the sequence of opening of each of the valves may be effected as required, merely by setting the angle of the cams in the proper relative manner. Therefore by this simple apparatus the volume 75 of liquid discharged from the tank periodically

through a discharge outlet or series of outlets can be readily controlled whereas in the case of a plurality of outlets, the sequence of discharge of each of the outlets may be selected.

Various valve constructions might readily be employed to suit requirements. A preferred construction of valve is illustrated in Figs. 1 and 8. The valve shown in Fig. 8 has characteristics similar to that shown in Fig. 1 but is slightly different in construction. In this case the member 14 is replaced by the body structure 62 flanged as at 63 and preferably bolted to the base of the tank 10 over a suitable orifice in the latter. A screw threaded spud 64 fastens into the base of the member 62 and forms the valve seat upon which the valve 65 is normally seated by means of the compression spring 66 which is compressed by the cap fitting 67 suitably secured to the member 62.

The operation of the device will be clearly apparent from the foregoing. The liquid in tank 10 is kept at a constant level to give an invariable flow and as the cam shaft rotates at the selected speed the valve will be opened and closed for intermittent periods of time which may be readily calculated and disclosed on the indicator according to the adjustment made. Therefore a constant periodic discharge of liquid is automatically provided for. Moreover in the case of discharging liquid from the tank 10 to various destinations through a plurality of pipe lines, not only is the periodic volume of the liquid discharged from each pipe line controlled but it may be varied as between various pipe lines as required and it may be discharged at varied times relative to one another of the discharge outlets.

In ore milling units the apparatus will, for example, assure a predetermined and unvarying lime content in the solutions with increase in cyanide strength thus making it possible to reduce the total daily amount of cyanide added to

the system while maintaining uniform controlled condition of the solution. It will be obvious however that the invention has a substantially wide application. Since it will handle any solution, emulsion or suspension it is of course adaptable for periodic feeding of liquid in other fields and is capable, for instance, of practical application in the addition of any reagent in water works, chemical plants, etc.

10 While a preferred form of apparatus has been shown, this apparatus is, of course, capable of variation and yet retaining its generally simple construction. Due to its simplicity it can be installed and maintained with minimum of cost and effort.

15 What I claim as my invention is:

In a device for periodically operating a valve from a normal position, a frame, a valve actuating arm pivotally mounted on said frame, said 20 arm having a telescoping section, control means for telescoping said telescoping section, a cam, drive means for said cam, the free end of said telescoping section being formed for engagement with said cam, a dial, a pointer for said dial, a 25 link and gear system connecting said pointer and said telescoping section of said arm.

JOSEPH EMILE EVERARD.
